UNITED STATES PATENT OFFICE.

JAMES SAMUEL JONES, OF CRUTCHFIELD, KENTUCKY.

BAG-HOLDER OR BILL-FILE.

SPECIFICATION forming part of Letters Patent No. 406,047, dated July 2, 1889.

Application filed February 2, 1889. Serial No. 298,515. (No model.)

To all whom it may concern:

Be it known that I, JAMES SAMUEL JONES, a citizen of the United States, residing at Crutchfield, in the county of Fulton and State 5 of Kentucky, have invented new and useful Improvements in Bag-Holders or Bill-Files, of which the following is a specification.

The invention relates to improvements in bag-holders or bill-files; and it consists in a 10 certain novel construction and combination of devices, fully described hereinafter in connection with the accompanying drawings, and specifically pointed out in the appended claims.

In the drawings, Figure 1 is a perspective 15 view of a bag-holder embodying my improvements. Fig. 2 is a similar view showing the manner of applying the bags thereto. Fig. 3 is a similar view of the lower end of the same with the movable disk removed to show the 20 base.

Referring by letter to the drawings, A designates the frame of the holder, having a ring B at its upper end to be engaged with a suitable hook or nail on the wall or counter, and 25 C designates a curved guide-rod at the lower end of the said frame, which is provided with the lower and upper parallel legs c and c'. The lower leg of this guide-rod is preferably 30 formed integral with the lower end of the frame, and is connected thereto by the coiled base D. The lower leg of the guide-rod is thus arranged perpendicular to and at the center of the said base. The ring B at the upper end of the frame is also preferably 35 formed integral therewith, and an arm E extends forward from the lower side of the ring and perpendicular to the frame, and is provided at its outer or free end with a loop F.

G represents a movable spring-arm, which 40 is connected by an eye g at its upper end to the loop F, and is provided at its lower end with a hook H, which slides on the lower leg of the guide-rod. A spring-coil I is formed at the center of the said arm, and is connected 45 to a loose hook K, which is normally engaged with the frame of the holder, as shown in Fig. 1 of the drawings, to hold the lower free end of the spring-arm depressed.

L represent small disks, of any desired 50 number, which are provided with central perforations I and slide on the guide-rod, and they are rearwardly flanged at their periph-

eries, as shown at M. These disks may be arranged on the upper leg of the guide-rod; but they are normally arranged on the lower 55 leg, in which position the hooked or free end of the spring-arm will bear thereon and hold them firmly in position.

To apply bags or bills to the improved holder, the loose hook is disengaged from the 60 frame, and the disks are moved up on the upper leg of the guide-rod, with the exception of one, which is arranged against the base D. Two bags are now arranged at their corners on the said disk on opposite sides of the lower 65 leg of the guide-rod, and then a second disk is moved down and pressed against the outer sides of the bags. Two other bags are now arranged in the same position, and a third disk is arranged against them, and so on until the entire number of disks is employed, 70 after which the spring-arm is arranged in the operative position, as described, and the loose hook engaged with the frame. The bags are not firmly held in position, and may be disengaged from the holder singly by pulling them downward; but the shape of the disks and the pressure which is exerted on them by the spring-arm prevents the accidental displacement of the bags. 75

The improved holder is formed entirely of wire, in three pieces—namely, the frame, the spring-arm, and the loose hook—and, if preferred, the spring-arm may be formed integral with the outer end of the arm E, thereby 85 still further reducing the number of parts. 80

Having thus described the invention, I claim—

1. In a bag-holder or bill-file, the combination, with means for supporting the same, of 90 a horizontal guide-rod having an enlarged base at one end, of disks movably mounted on said guide-rod, and a spring normally pressing said disks against said base, as and for the purpose set forth. 95

2. In a bag-holder or bill-file, the combination, with a frame comprising a substantially- 100 vertical body A, a U-shaped guide-rod C, its arms standing at right angles to said body, its lowermost extremity being integrally connected therewith and its uppermost extremity being clamped thereto, of the disks L, movably mounted upon the lowermost arm of said guide-rod, and a spring G, connected to the

frame and pressing said disks normally against the body A, as and for the purpose set forth.

3. In a bag-holder or bill-file, the combination, with a frame comprising a substantially-vertical body A and a U-shaped guide-rod C, its arms standing at right angles to said body, its lowermost extremity being integrally connected therewith and its uppermost extremity 10 being clamped thereto, of the disks L, movably mounted upon the lowermost arm of said guide-rod, the spring-arm G, pivotally connected at its upper end to said body S and its lower end bearing against the outer of said 15 disks, and the hook K, attached to said spring-arm intermediately between its ends and adapted to engage the body A, to deflect the arm G and cause it to exert a yielding pressure upon said disks, as and for the purpose 20 set forth.

4. In a bag-holder or bill-file, the combination, with the guide-rod C, having the integral base D, of the disks L, mounted on said guide-rod and provided with flanged periph-

eries M, and a spring-arm pressing said disks 25 toward said base to hold them in contact, as and for the purpose set forth.

5. In a bag-holder or bill-file, the combination of the frame A, provided at its upper end with an eye B and a lateral arm E and at its 30 lower end with a curved guide-rod C, all said parts being integral, the loose disks L, mounted on said guide-rod, the spring-arm G, pivoted at its upper end to an eye in said lateral arm E and provided at its lower end with a hook 35 H and at its center with a coil I, and the hook K, pivoted to said coil I and adapted to engage the body of the frame A for causing said hook to bear with yielding pressure against the disks L, as and for the purpose set 40 forth.

In testimony that I claim the foregoing as my own I have hereto affixed my signature in presence of two witnesses.

JAMES SAMUEL JONES.
